CLAIM

The ornamental design for a round lock, as shown and described.

DESCRIPTION

FIG. 1 is a perspective view of a round lock with the lock closed;

FIG. 2 is a front view;

FIG. 3 is a rear view;

FIG. 4 is a side view;

FIG. 5 is the other side view;

FIG. 6 is a top view;

FIG. 7 is a bottom view;

FIG. 8 is an exploded perspective view with the lock open;

FIG. 9 is a perspective view of the lock detail in the environment in which it may be used;

FIG. 10 is a front view of the lock detail in the environment in which it may be used;

FIG. 11 is a perspective view showing the lock in the environment in which it may be used;

FIG. 12 is a perspective view showing an alternative embodiment of the lock in the environment in which it may be used;

FIG. 13 is a front view of the alternative embodiment; and, FIG. 14 is a perspective view of the alternative embodiment the opposite perspective view is a mirror image.

The broken lines are shown for illustrative purposes only, and form no part of the claimed design.

The surface(s) or portion(s) of the article not shown in the drawing or described in the specification form(s) no part of the claimed design.
